ABSTRACT: A bin and support clamp assembly which is useful in displaying merchandise at the front edge of a support shelf or the like. The bin portion includes a front wall and a rear wall and a bottom, all preferably made from cardboard material. The clamp portion includes a U-shaped leg which extends along the three portions of the bin to securely hold the bin. The clamp also includes a fastening portion for attaching the entire assembly to a support shelf or the like, and the fastening portion and the U-shaped leg are relatively oriented so that the bin is tilted or oblique to the horizontal position of the shelf, for optimum support and display of the merchandise.

PATENTED MAR 2 1971

ATTORNEY

BIN AND SUPPORT CLAMP ASSEMBLY

This invention relates to a bin and support clamp assembly. More particularly, it relates to that type of assembly which is useful in supporting and displaying merchandise on a store shelf or the like. The assembly is readily attached to and removed from a supporting shelf or the like, and it is arranged to make a functional and an attractive presentation.

BACKGROUND OF THE INVENTION

The prior art is already aware of numerous arrangements of assemblies of bins and clamps for releasably attaching the assembly to support members, such as ledges or shelves. However, the assemblies of the prior art are not arranged for the particular utility of the assembly of this invention, and they are not sufficiently functional and attractive, compared to the assembly of this invention. Still further, the prior art assemblies of the type mentioned are not capable of being manufactured from lightweight and inexpensive materials, but yet being sturdy for supporting substantial weight and doing so in positions which give optimum support and display characteristics to the goods in the bin.

Accordingly, it is the object of this invention to provide an assembly of a bin and support clamp which is capable of being readily and easily attached to a supporting shelf or the like, is a lightweight but yet capable of supporting goods of a substantial weight, is disposed in an optimum position for securely holding the goods, and which is arranged with a minimum of interference with the use of the supporting shelf and a lack of interference with the goods held in the bin. These several objects are also accomplished by means of an easily manufactured and inexpensive assembly of a bin and supporting clamp.

More specifically, it is an object of this invention to provide a bin and supporting clamp assembly which is particularly useful in supporting magazines or paperback or like types of reading material, and to do so at an angle which renders the paper material readily readable from the front of the assembly and which renders the material self-supporting in its extent above the top level of the assembly itself. In accomplishing this object, the paper type of reading material is disposed in an inclined position so that a person can readily read it, and so that material is leaning back so that it is in a self-supporting position, as mentioned.

BRIEF DESCRIPTION OF THE DRAWINGS

FIG. 1 is a rear perspective view of a preferred embodiment of this assembly, mounted on a supporting shelf.

FIG. 2 is an enlarged sectional view taken on the line 2-2 of FIG. 1.

FIG. 3 is a bottom plan view of a fragment of FIG. 2.

FIG. 4 is a front elevational view of a fragment of FIG. 2, and with portions thereof broken away.

DETAILED DESCRIPTION OF THE PREFERRED EMBODIMENT

The bin and support clamp assembly is designated 10, and it is shown on a supporting shelf 11. The shelf 11 may be a store shelf which has other merchandise distributed along the shelf 11 in the usual arrangement, and the assembly 10 is therefore arranged to extend forwardly of the shelf 11 and to virtually not interfere with the use of the shelf 11. Nevertheless, the assembly 10 can be attached to and removed from the shelf 11, and it can be positioned along the shelf 11, as desired. Further, it will be understood that the assembly 10 can support merchandise or other goods, and such merchandise may be reading material made of sheets of paper, such as magazines, newspapers, paperback-type books, children's reading and activity books, or the like. With respect to this type of paper material, there is concern in having the goods stand up so that it can be properly seen and displayed. The assembly 10 is arranged to support the sheet material in an upright position,

and this is done by having the assembly 10 in an orientation which will permit the sheet material to be slightly tilted rearwardly, as indicated in FIG. 2 as indicated by reference numeral 12. Of course it will be understood that the shown magazines or books 12 extend substantially above the assembly 10, and they may actually extend at least again as high as the assembly 10 as it is seen in FIG. 2, for instance. Nevertheless, the books 12 will stand in a planar but slightly tilted position.

10 The bin 10 is made of cardboard material which is sufficiently stiff and sturdy to at least support itself in the plane in which it extends. The bin 10 is shown in its final or folded form, and it includes one piece of card material or stock which is cut and folded in form shown: FIGS. 1 and 2 show the bin 10 includes a front wall 13, a rear wall 14, and a bottom 16. FIG. 2 particularly shows the extent of the one piece of card material in that a first portion 17 extends from its free end 18 upwardly and into a top edge portion 19 and then downwardly in the portion 21 which is integral with and extends to the bottom 16. The one piece continues through the portion 22 in the front wall 13, and into the top edge 23 of the front wall, and into the portion 24 of the front wall. The one piece then terminates in an end 26. In a similar form of folding, the one piece of card material also extends upwardly from the bottom 16 in an end wall 27 which extends through the end wall top edge 28 and downwardly into the interior of the bin 10, as the portions 17 and 24 extend downwardly. Also, the end wall 27 has two end portions extending inwardly on the bin 10 and integral with the inner and outer walls or faces forming each end portion. Thus, the bin has its end wall 28 showing the end portions 29 and 31 extending into the front wall 13, and FIG. 2 also shows the end wall 28 having its end flaps or portions 32 and 33 extending into the rear wall 14. For reasons of optimum strength in the bin 10, the portions 32 and 33 extend further into the rear wall 14 than do the portions 29 and 31 extend into the front wall 13. This difference in extent of these flaps described will also be more fully appreciated and mentioned later.

40 Finally, it will be seen that the ends 18 and 26 respectively extend into openings 34 and 36 formed in the one piece of material described. That is, tabs 37, as best seen FIG. 4, are on these ends 18 and 26 to extend in a locked relationship with the openings 34 and 36 to retain the box in the rectilinear form shown.

Like the tab 37 on the front wall edge 26, the rear wall edge 18 has a tab 38 which projects into the opening 34 to interlock therewith.

50 With the box made from one piece of card material as described, it presents the front and rear walls and the bottom described, and the front wall has the spaced-apart portions 22 and 24 which define an opening 39 useful for a purpose mentioned later.

55 A clamp generally designated 41 forms a part of the assembly shown, and the clamp includes a U-shaped leg portion generally designated 42 and consisting of the upstanding free end 43, the bottom portion 44, and the upstanding rear portion 46. Also, the clamp 41 includes the fastening portion which has the threaded member 47 extending through clamp portion 48 carrying a nut 49. The clamp has an extension 51 which cooperates with the threaded member 47 for releasably fastening the entire assembly to the shelf 11.

60 Also, the clamp has a bite portion 52 which extends over the upper edge 19 of the rear wall 14 of the bin 10. The bite portion 52 has spaced-apart abutment surfaces 53 and 54 which flank the front and end surfaces, respectively, of the bin rear wall 14, as shown in FIG. 2. Of course it will be understood that the box or bin 10 is sufficiently pliable to fit it into the assembled relation with the clamp 41, and particularly so with the bite portion 52. Thus the clamp 41 is made of a rigid material, such as a lightweight plastic material, and it will be also seen that the leg 43 extends snugly into the opening 39 while the clamp leg 44 extends in contact with the bottom 16 of the box 10.

With the assembly described, it will therefore be seen that the clamp 41 securely holds the bin rear wall 14, by the clamp bite portion 52 and by the leg 46 extending along the rear wall portion 21, and the clamp 41 also extends below the bin 10, in the clamp portion 44, and the clamp 41 finally extends in firm holding relation with the bin front wall 13 by extending into the opening 39. Therefore, the clamp 41 does not extend across the upper opening of the bin, nor does it in any way interfere with the full use of the box or bin 10. Still further, the clamp 41 is concealed from the front of the bin 10 so that the front wall 13 can have a printing thereon and the clamp 41 will not extend over the printing or otherwise be apparent from the front view of the bin 10. Thus it is significant that the clamp leg 43 extends into the opening 39 which is defined by the front wall 13 and opens thereon at the bottom edge 56 of the front wall 13. That is, the opening 39 is a continuation of the opening 36, as shown in FIG. 3. The clamp leg 43 is in snug contact with the inner surfaces 57 of the front wall portions 22 and 24, and the leg 43 extends over halfway up on the front wall 13 for firm support of the box 10.

It will also be seen in FIG. 2 that the clamp 41 has its fastening means or portion, including the portion 46, oblique with respect to the orientation of the U-shaped leg portion 42. This relationship places the box or bin 10 in a rearwardly inclined or tilted position, as seen in FIG. 2, so that the magazines 12, or the like, will recline in a desired and self-supporting position. The shelf 11 is considered to be horizontally disposed, and the fastening means or portion of the clamp 41 is considered to be vertically oriented, but the U-shaped leg portion 42 is therefore oblique with respect to the vertically oriented fastening portion of the clamp 41, as shown in FIG. 2.

I claim:

1. In an assembly of a bin and a support clamp for mounting the assembly on a support, a bin having an upright front wall with a bottom edge and having a rear wall terminating in an upper edge, a clamp attached to said bin and including fastening means for removably mounting said assembly onto said support, the improvement comprising said upright front wall having an opening extending upwardly therein from said bottom edge of said upright front wall, said upright front wall having two spaced-apart portions extending completely across said opening on both the front face and rear face of said upright wall for defining and concealing said opening along said front face and said rear face, said clamp including a leg extending upwardly and into said opening from said bottom edge and being dimensioned to be in snug contact with both

said spaced-apart portions and to span the full distance between said spaced-apart portions, the length of said leg being sufficient to extend into said opening at least halfway up on said front wall and being concealed by said front wall, and

5 said clamp including a bite portion snugly engaged with said upper edge of said rear wall for securely holding said rear wall.

2. The subject matter of claim 1, wherein said fastening means of said clamp is both obliquely disposed and has different upright orientation relative to said leg for supporting 10 said bin in a tilted position relative to the vertical direction and when said fastening means is vertically oriented.

3. The subject matter of claim 2, wherein said bin includes a bottom extending between said front wall and said rear wall, said leg being U-shaped and extending from said bite portion 15 and into said opening and in supporting contact with said rear wall and said bottom and said front wall throughout the extent of said leg.

4. The subject matter of claim 3, wherein said bin is of cardboard material, and said bite portion includes spaced-apart 20 surfaces facing each other and respectively extending in contact with opposite faces of said upper edge of said rear wall.

5. In an assembly of a bin and a support clamp for mounting the assembly on a horizontally disposed shelf, a bin having a front wall and rear wall, parallel to each other, and an interconnecting bottom, a clamp attached to said bin and including 25 fastening means for removably mounting said assembly onto said shelf, the improvement comprising said clamp including a shelf-engaging portion extending horizontally along said shelf and including said fastening means, said clamp including a bin-engaging portion having a bite portion engaged with said rear wall and having a U-shaped leg extending in three rectilinearly related lengths with each of said lengths being respectively disposed along each of said front wall and said bottom and said rear wall, the orientation of said bin-engaging 30 portion being upright in its U-shape and tilted relative to the vertical direction and thereby being orientated obliquely to said shelf-engaging portion to support said bin at a tilted orientation relative to said horizontally disposed shelf.

6. The subject matter of claim 5, wherein said length of said 40 U-shaped leg at said front wall extends into said front wall and is concealed by said front wall.

7. The subject matter of claim 6, wherein said bin is of a cardboard material, and said bite portion includes two spaced-apart surfaces disposed facing each other and flanking the 45 upper edge of said rear wall for holding said upper edge.
